FURNITURE LEG GLIDER

Robert E. Miller, Bronxville, N. Y.

Application April 9, 1949, Serial No. 86,473

2 Claims. (Cl. 16—30)

1

My present invention relates generally to gliding attachments for furniture legs.

A general object of the invention is to provide certain improvements in the type of gliding attachment for use with a furniture leg having an open tubular lower end. This type of glider consists essentially of a closure plate adapted to close the leg end and provided with a margin adapted to lie beneath and fit against the edge of the leg end, a gliding element secured to the underside of the closure blade, leg attaching means comprising spring arms secured to and extending upwardly from the upper side of the closure plate. When these spring arms are entered into the open tubular lower end of the leg, they are pressed into frictional engagement with the interior of the leg end.

One of the more specific objects of the invention lies in an improved glider supporting means whose insertion into the leg end is facilitated and may be accomplished without calling for the use of any extraneous tools.

Another specific object of the present invention is to provide a gliding attachment which may be satisfactorily employed with a furniture leg of the type whose axis is at an oblique angle to the floor. This type of furniture leg presents a special problem, since the gliding element must lie flat against the floor in order to be properly effective, whereas the arms of the attachment strip must be capable of entering and establishing firm securement within the oblique leg end. The present improved gliding attachment is specially designed to comply with the peculiar requirements of an oblique furniture leg.

In the preferred embodiment herein described, the aforementioned two arms are made integrally from a strip by a bending operation because thereby the objectives of my invention are more fully attained.

Another object of the invention is to provide a construction having the special advantages and capabilities referred to, yet capable of manufacture in economical fashion and without material deviation from the procedures involved in the manufacture of the ordinary type of gliding attachment.

I achieve the foregoing objects and advantages, and such other objects and advantages as may hereinafter appear or be pointed out, in the manner illustratively exemplified in the accompanying drawings, in which:

Fig. 1 is an elevational cross-sectional view through a tubular leg end of oblique character, 55

2

showing an improved gliding attachment in position thereon;

Fig. 2 is a cross-sectional view taken substantially along the line 2—2 of Fig. 1;

Fig. 3 is a transverse cross-sectional view taken substantially along the line 3—3 of Fig. 1;

Fig. 4 is a transverse cross-sectional view taken substantially along the line 4—4 of Fig. 1;

Fig. 5 is a view similar to Fig. 1 showing the attachment applied to a slightly different type of furniture leg; and

Fig. 6 is a cross-sectional view taken substantially along the line 6—6 of Fig. 5.

The furniture leg which I have chosen to illustrate in Figs. 1—4 has an open tubular lower end 10 which is substantially square in cross-section (see Figs. 3 and 4). The lower edge of the tube lies in a plane parallel to the floor 11, and the axis of the tube is at an oblique angle to the floor, substantially as shown.

At 12 I have shown a square closure plate forming part of the gliding attachment. This plate is usually and preferably composed of metal, and it is provided with a margin 13 which is adapted to lie beneath and fit against the end edge of the tube 10. Preferably, the margin 13 is offset downwardly from the body of the plate 12, so that the major part of the plate lies within the confines of the furniture leg.

Secured to the underside of the closure plate 12, preferably by means of a rivet 14 or the like, is a gliding element which consists of a rubber part 15 and a highly polished metallic part 16. The rivet 14 secures the part 15 in position beneath the body portion of the closure plate 12, and the metallic part 16 is substantially cup-shaped, the lower surface being flat and smooth and the upper edge being in-turned to grip the part 15.

Two arms are secured to the upper face of the closure plate 12. These arms are herein disclosed as formed integrally from a strip which, in its original unbent condition, is indicated by the dot-and-dash lines 17 in Fig. 1. The same rivet 14 which secures the part 15 in position can be utilized to secure the strip 17 to the upper face of the plate 12. In accordance with my invention, the point of securement is at the midpoint of the strip 17.

In completing the manufacture of the device, the strip 17 is bent upwardly along transverse lines 18 and 19 which are unequally distant from the midpoint referred to. As will be apparent from an inspection of Figs. 1 and 4, the bend 18 lies further from the rivet 14 than the bend

19. This results in producing a substantially U-shaped attachment strip, whose arms are of unequal length, i. e., the arm 20 is somewhat shorter than the arm 21.

The arms 20 and 21 are bent upwardly so that the axis of the U has an obliquity which conforms to that of the leg end for which the attachment device is intended. The longer U arm, i. e., the arm 21 in the illustrated device, lies uppermost.

The distance between the bends 18 and 19 is less than that between opposite walls of the tube 10, and the arms of the U-shaped attachment strip are caused to diverge upwardly, as shown. Along transverse lines 22 and 23, the arms are bent toward each other so that the upper parts 15 24 and 25 converge toward each other. If desired, the extreme ends of the arms may be bent into substantially parallel relationship, as shown, but this is not essential.

The bends 22 and 23 are along lines which are substantially equidistant from the free ends of the arms (hence at unequal distances from the bends 18 and 19). As a result, elbows are defined which press outwardly against opposite walls of the tube 10 in a plane substantially transverse to the axis of the leg end. This establishes a firm frictional engagement between the attachment strip and the leg end.

In accordance with the present invention, the angle between the converging parts 24 and 25 of the arms (designated by the reference numeral 26 in Fig. 1) is an acute angle, i. e., it is less than 90°. This angularity is important because it permits the device to be inserted into the furniture leg without calling for the use of any extraneous tools. That is to say, as a result of the springiness of the arms of the U, they normally tend to assume a position farther apart than that shown in Fig. 1. When the device is inserted into the leg end, the arm portions 24 and 25 encounter opposite edge portions of the leg, and a camming action ensues, i. e., upward pressure on the attachment device causes the arms to move toward each other and ultimately assume the relationship shown in Fig. 1. This camming action is made possible by the angularity between the parts 24 and 25.

The usefulness of the invention is not restricted to furniture legs of square or rectangular cross-section, and I have illustrated a leg of circular cross-section at 27 in Figs. 5 and 6. In this case, the gliding element 28 is secured, as before, to the under side of a closure plate 29, while a U-shaped attachment strip 30, having U arms 31 and 32, is secured as at 33, to the upper face of the plate 29. The plate 29 has a margin 34 which presses upwardly against the lower edge of the tubular leg end 27. The plate 29, and the margin 34, are shaped to conform to the leg end, i. e., they are substantially circular or slightly elliptical.

Obviously, because of the curved nature of the leg end, the arm 31 bears against the wall of the tube at the two end points 35 and 36 (see Fig. 6), while the arm 32 similarly presses outwardly at its ends 37 and 38. In other respects, however, the mode of application and of functioning of the gliding attachment is the same as that hereinbefore described in connection with Figs. 1-4.

In general, it will be understood that those skilled in the art may obviously make changes in the details herein described and illustrated, without necessarily departing from the spirit and scope of the invention as expressed in the appended claims.

Having thus described my invention and illustrated its use, what I claim as new and desire to secure by Letters Patent is:

1. A gliding attachment for a furniture leg having an open tubular lower end whose edge is in a plane parallel to the floor and whose axis is at an oblique angle to the floor, comprising a closure plate adapted to close said leg end and provided with a margin adapted to lie beneath and fit against said edge, a gliding element secured to the underside of said plate, and a U-shaped attachment strip whose base is secured to the upper side of said plate and whose arms are bent transversely of the strip material to meet the base in acute angles whereby its axis has an obliquity conforming to that of said leg end, the arms of said strip extending upwardly for entry into the leg end, the lower parts of said arms being in divergent relation to each other, the upper parts being bent toward each other to define elbows between said lower and upper parts, said arms having a springiness tending to spread said elbows into frictional engagement with the interior of said leg end.

2. A gliding attachment for a furniture leg constructed as set forth in claim 1, wherein said elbows are formed in the arms at such unequal distances from the U-base as to effect said frictional engagement in a plane substantially transverse to the said axis of said leg end.
